UNITED STATES PATENT OFFICE.

CARL J. SCHUSTER, OF MILWAUKEE, WISCONSIN.

BOTTLE CLOSURE.

Application filed May 8, 1925. Serial No. 28,825.

The present invention relates to improvements in caps of that type which are adapted to be used as closures in connection with milk bottles or other wide mouthed containers, and among the objects of the invention is to provide a cap of this character which embodies novel features of construction, whereby it can be inexpensively molded from paper pulp or the like and has a thicker and more elastic body formation than can be obtained in bottle caps which are constructed by shaping or forming a sheet of cardboard or like material.

Further objects of the invention are to provide a bottle cap of this character which will securely close the bottle, which has a flange extending over the top of the bottle to prevent contamination of the surface over which the contents of the bottle flow when poured from the bottle, which has a smooth outer surface free from depressions in which dirt and foreign matter may collect, which will not warp or lose its shape, which has greater strength than a thin paste board cap and which can be used in the standard automatic capping machines.

Several different embodiments of the invention have been shown and described in detail for illustrative purposes, although it will be understood that many modifications and changes can be made in the details of construction without departing from the spirit of the invention or the scope of the appended claims.

For a full understanding of the invention reference is to be had to the following description and accompanying drawings, in which,

Figure 1 is a bottom plan view of a bottle cap which is constructed in accordance with the invention.

Figure 2 is a sectional view through the bottle cap shown by Figure 1.

Figure 3 is a view similar to Figure 2, showing a modified form of the invention.

Figure 4 is a similar view showing a still further modification of the invention.

Figure 5 is a sectional view through a bottle neck, showing the cap of Figure 4 applied thereto.

Figure 6 is a view similar to Figure 5 showing the cap with the lower lip or flange thereof as it is bent upwardly and compressed during the act of applying the bottle cap in position.

Figure 7 is a fragmentary sectional view

through a portion of a bottle neck having a cap constructed as shown by Figures 1 and 2 applied thereto.

Figure 8 is a similar view showing a cap constructed as shown by Figure 3.

Figure 9 is a fragmentary sectional view of a cap similar to that shown by Figures 1 and 2, but provided at the periphery thereof with an extended and downwardly curved flange adapted to fit partially around the exterior lip of the bottle mouth when the cap is in position.

Figure 10 is a similar view showing a modification in which a cap constructed as shown by Figure 3 is provided with an enlarged and downwardly curved marginal flange.

Figure 11 is a similar view showing a cap constructed in general as shown by Figure 4, being provided with a hollow body portion and an enlarged and downwardly curved marginal flange.

Figure 12 is a fragmentary sectional view through a portion of a bottle neck which is formed without an interior bead and has a cap such as that shown by Fig. 4 applied thereto, the lip of the cap being deflected upwardly and crowded against the walls of the bottle neck when the cap is finally seated in position.

Corresponding and like parts are referred to in the following description and indicated on all of the views of the drawings by like reference characters.

The bottle cap of this invention has a comparatively thick and substantial body portion which is molded from some suitable plastic material such as paper pulp, and in this respect is essentially different from the conventional bottle caps which are formed by bending and shaping sheet material such as cardboard. In all of the figures of the drawing the reference character A designates the body portion of the cap which is adapted to enter the mouth of the bottle and expand into a tight engagement therewith, and B a marginal flange which extends around the top of the body portion and is adapted to project over the normally exposed top or upper edge of the bottle neck and prevent contamination of this portion of the bottle which is usually exposed and over which the contents of the bottle must flow when they are poured from the bottle. The body portion A is comparatively thick so that it not only provides a tight and substantial closure

for the bottle, but renders it impossible for the bottle cap to become warped or lose its shape. The top or upper surface of the bottle cap is smooth and free from any indentations or pockets in which dirt and foreign matter might collect.

In the form of the invention shown by Figures 1 and 2 the periphery of the body portion flares downwardly, the marginal or edge portion being tapered, as indicated at 1, and terminating in a lip 2. The cap is intended to be applied to a bottle neck C of the general type illustrated by Figures 5 to 8 inclusive. The bottle neck is provided at 10 the mouth thereof with an interior contracted bead 3 and with an exterior enlargement 4. A bottle neck of this general type is preferable because there are no sharp corners or pockets in which dirt and filth may collect 15 and which are difficult to clean properly. When the bottle cap of Figures 1 and 2 is applied to a bottle the annular lip 2 thereof first curls upwardly as the cap is pressed downwardly into position and finally expands downwardly under the interior bead 3 of the bottle neck, as indicated by Figure 25. The marginal flange B then extends over the top of the mouth of the bottle and is held in a firm engagement therewith. The peripheral walls of the body portion A are then slightly indented by and in a tight engagement with the interior bead 3 of the bottle, while the lip 2 is in an expansive engagement with the lower portion of the 35 bead 3.

A modification is shown by Figure 3, in which the body portion A of the cap has cylindrical edge walls 5 and an annular flange or lip 6 at the lower edge of the cylindrical portion 5. When this bottle cap is forced into position the lower lip or flange 6 is first bent upwardly until it passes beyond the interior bead 3 of the bottle neck, whereupon it expands downwardly and outwardly, 45 as indicated by Figure 8. The top marginal flange B of the cap is then fitted on the top of the bottle neck and the cylindrical edge walls 5 of the cap are indented and engaged by the interior bead 3 of the bottle, 50 while the lip 6 is in an expansive engagement with the interior of the bottle neck below the bead 3.

Another modification is shown by Figure 4, in which the body portion A of the cap is provided at the periphery thereof with an annular rib 7, an annular lip or flange 8 being provided below the rib 7 at the lower end of the body portion. When the cap is forced into position upon the bottle the lip 8 at the lower end thereof is initially bent upwardly and compressed against the rib 7 by engagement with the interior bead 3 of the bottle neck, as indicated by Figure 6. When the cap is finally seated 65 the lip 8 clears the bead 3 of the bottle neck

and expands downwardly and outwardly below the same, as indicated by Figure 5. The rounded exterior wall of the annular rib 7 is then indented by and held in a firm and tight engagement with the bead 3, so that it cooperates with the lip 8 to provide a secure and tight closure for the bottle. The expansive action of the lip 8 also tends to seat the cap upon the bottle neck and hold the top flange B thereof firmly against the top 70 of the bottle.

The modified form of the invention which is shown by Figure 9 is identical with that shown by Figure 2, with the exception that the top marginal flange B is formed with a 75 downwardly curved extension 9. This enlarged extension may be used when it is desired to provide a cap which will extend over and cover not only the top of the bottle mouth but also a portion of the rounded enlargement at the exterior thereof.

In a similar manner the modification shown by Figure 10 is identical with the form illustrated by Figure 3, with the exception that the top marginal flange B has an extension 9 which is curved downwardly. This form of the invention may be used where it is desired to cover a larger portion of the normally exposed area at the mouth of the 90 bottle.

The modification shown by Figure 11 has a body portion which is constructed similar to that of Figure 4, although the central portion thereof is hollowed out on the under-side, as indicated at 10, such a construction being possible in some instances where it is desired to save material. This modification also shows the top marginal flange B as formed with an extension 9 which is curved downwardly and serves the same 105 function as in the constructions of Figures 9 and 10.

The cap may be used upon a bottle neck which is formed without an interior bead 3, a fragmentary portion of such a bottle neck being shown at C' on Figure 12. When the cap is forced into position the lip 8 is deflected upwardly and caused to crowd tightly against the interior of the bottle neck, and the lip retains this position when the cap is finally seated, for the reason that there is no interior bead with a clearance space below the same to provide for the expansion of the lip after it has been forced downwardly below the bead. With a bottle neck 110 having straight interior walls, as shown by Figure 12, the lip 8 will be deflected upwardly and compressed inwardly so as to be crowded against the interior walls of the neck when the cap is finally seated in position. The annular rib 7 of the cap will also be crowded tightly against the bottle neck and the combined action of the rib 7 and lip 8 will insure a tight sealing of the bottle.

As previously stated, it is intended that 120

the bottle cap shall be molded from paper pulp or similar plastic material, and the body portion is thereby made thicker and stronger than would be possible in a bottle 5 cap which is formed by bending and shaping paper or cardboard. The cap is thereby given a substantial body portion which will not warp or lose its shape, which has sufficient resiliency to expand into a tight engagement 10 with the mouth of the bottle and accommodate itself to any little irregularities in the shape of the bottle mouth. The wide peripheral edge of the comparatively thick molded bottle cap is adapted to be 15 tightly compressed against the interior of the bottle neck when the cap is placed in position, the annular lip at the bottom of the cap having at the same time an expansive engagement with the interior of the 20 bottle neck. The invention also provides a bottle cap which can be handled successfully in the conventional bottle capping machines and which can accordingly be applied to the bottles with great rapidity.

25 Having thus described my invention what I claim as new and desire to secure by Letters Patent is,

1. A one piece bottle cap formed from paper pulp and comprising a comparatively thick and substantially cylindrical body portion having a wide peripheral edge, said body portion being provided with an integral annular lip projecting outwardly from the bottom portion thereof, said lip being flexible and being adapted to be flexed upwardly between the interior of the bottle neck and peripheral edge of the body portion when the cap is forced in position.
2. A one piece bottle cap formed of paper pulp and comprising a comparatively thick and substantially cylindrical body portion having a wide peripheral edge, the top of the body portion being formed with a marginal flange adapted to extend over the top 45 of the bottle, while the bottom of the body

portion is formed with an outwardly projecting annular lip, said lip being flexible and being adapted to be flexed upwardly between the interior of the bottle neck and the peripheral edge of the body portion when 50 the cap is forced in position.

3. A one piece bottle cap molded from pulp and comprising a substantially cylindrical body portion adapted to enter the mouth of the bottle and formed with an annular rib, and an annular lip which is arranged below the rib, the rib being adapted to be compressed against the interior of the bottle neck while the lip is flexible and is adapted to maintain an expansive engagement 60 with the interior of the bottle neck.

4. A one piece bottle cap molded from pulp and comprising a substantially cylindrical body portion adapted to enter the mouth of the bottle and provided at the top thereof with a marginal flange adapted to extend over the top of the bottle neck, said body portion being formed with an annular rib and also with an annular lip, the rib being adapted to be compressed against 70 the interior of the bottle neck while the lip is flexible and maintains an expansive engagement with the same.

5. A one piece bottle cap molded from pulp and comprising a substantially cylindrical body portion adapted to enter the mouth of the bottle and formed with an annular rib and an annular lip, the rib being adapted to be compressed against the interior of the bottle neck, while the lip is 75 flexible and maintains an expansive engagement therewith, the top of the body portion being formed with a marginal flange which is adapted to extend over the top of the bottle and terminates in a downwardly curved 80 extension adapted to fit around the exterior of the bottle.

In testimony whereof I affix my signature.

CARL J. SCHUSTER.
